(57) **CLAIM**

We claim the ornamental design for a foldably constructed pallet, as shown and described.

DESCRIPTION

FIG. 1 is a top front isometric view of a bottom blank of a foldably constructed pallet in an unfolded configuration.

FIG. 2 is a top plan view of FIG. 1.

FIG. 3 is a bottom plan view of FIG. 1.

FIG. 4 is a front elevation view of FIG. 1.

FIG. 5 is a rear elevation view of FIG. 1.

FIG. 6 is a right side elevation view of FIG. 1.

FIG. 7 is a left side elevation view of FIG. 1.

FIG. 8 is a top front isometric view of a top blank of a foldably constructed pallet in an unfolded configuration.

FIG. 9 is a top plan view of FIG. 8.

FIG. 10 is a bottom plan view of FIG. 8.

FIG. 11 is a front elevation view of FIG. 8.

FIG. 12 is a rear elevation view of FIG. 8.

FIG. 13 is a left side elevation of FIG. 8.

FIG. 14 is a right side elevation of FIG. 8.

FIG. 15 is an exploded view of the foldably constructed pallet constructed by folding the bottom blank of FIG. 1 and the top blank of FIG. 8 along the fold lines shown by the dotted lines and connecting the folded top blank and the folded bottom blank together.

FIG. 16 is a top front isometric view of a foldably constructed pallet by connecting the folded bottom blank and the folded top blank of FIG. 15 together.

FIG. 17 is a top plan view of FIG. 16.

FIG. 18 is a bottom plan view of FIG. 16.

FIG. 19 is a front elevation view of FIG. 16, with the rear elevation view being a mirror image thereof; and,

FIG. 20 is a right side elevation view of FIG. 16, with the left side elevation view being a mirror image thereof.
The dotted lines represent fold lines. The solid lines adjacent the dotted lines form part of the claimed design.
